UNITED STATES PATENT OFFICE.

FRANK E. SHRINER, OF DETROIT, MICHIGAN.

COLUMN-CLAMP.

1,275,313.

Specification of Letters Patent. Patented Aug. 13, 1918.

Application filed May 22, 1916. Serial No. 99,053.

To all whom it may concern:

Be it known that I, FRANK E. SHRINER, a citizen of the United States, residing at Detroit, county of Wayne, State of Michigan, have invented a certain new and useful Improvement in Column-Clamps; and declare the following to be a full, clear, and exact description of the same, such as will enable others skilled in the art to which it pertains to make and use the same, reference being had to the accompanying drawings, which form a part of this specification.

This invention relates to clamps for concrete column forms and its object is a cheap and efficient device for binding together the forms utilized in the construction of a concrete column. In the building of such columns the form is usually made of several separate pieces extending longitudinally between the base and cap of the column and these pieces are held in position by a number of clamps engaging tightly about the form and spaced apart vertically thereon. An object of this invention is a clamp having a base adapted to engage against the form provided with a chain adapted to pass about the form and a lever by means of which the chain may be drawn tightly about the form. An additional object of the invention is a clamp having a lever for drawing the chain about the form so arranged that, when the chain is drawn taut by movement of the lever to binding position, the strain tends to hold the lever in such position. Another object of the invention is a device of the character described provided with a lever as stated, that is adjustable in position relative to its support. These objects and the several novel features of the invention are hereinafter more fully described and claimed as shown in the accompanying drawings in which—

Figure 1 is a side view of my improved clamp showing the lever in locked position, a portion of the form encircling chain only being shown.

Fig. 2 is a plan view of the clamp.

Fig. 3 is a section of the column and form showing the clamp in position.

Fig. 4 is a detail showing the form of the aperture in which the lever is pivotally mounted and by means of which the position of the lever may be altered.

Fig. 5 is a detail showing the method of fastening the chain to the base of the clamp.

Fig. 6 is a detail of the jaw or hook engaged by the free end of the chain.

Similar characters refer to similar parts throughout the drawing and specification. 60

The device consists of a base plate or member 1 having a flat surface for engaging against the side of the form, as may be understood from Figs. 1 and 3. As may be understood from Fig. 2, side plates or members 2 and 3 are provided extending upward at a right angle to the base. Each of these members 2 and 3 is apertured as shown at 7 in Fig. 4 and the lever 4 is provided with a forked end 5, each fork of which is provided with a stud or bolt 6 extending through the apertures respectively. The apertures 7 are scroll shaped in form and the bolts 6 may occupy a position indicated at 8 or at 9, as shown in Fig. 4, in either of which positions the lever is pivotally supported. A lug 10 extends upward between the portions 8 and 9 of the aperture, and when the lever is positioned at the point 9 of the aperture, the lug 10 takes the strain imposed in binding the device about the form.

A movable member 11 is pivotally supported in the fork of the lever 4 at 12 and the opposite end of the member is provided with two blocks 13 and 14 recessed as indicated at 15 in Fig. 6, to receive a link of the chain 16, which is passed about the form as may be understood from Fig. 3. The opposite end of the chain is secured to the base plate 1, which is recessed at 17 to receive a link of the chain as shown in Fig. 5 and an apertured reinforcing member or block 18 is secured to the plate 1 through which the end link of the chain passes. By this arrangement the chain is permanently secured to the plate 1 and the clamp and chain are thus secured together, preventing a loss of either part thereof when not in use.

In operation a column form is first set up, the plate 1 set in position against one portion thereof, as will be understood from the drawing, and the lever 4 raised to position indicated by dotted lines *b*. This operation moves the member 11 forwardly to such position that a link of the chain 16 may be passed between the recessed blocks 13 and 14 as indicated in Fig. 2. By then moving the lever backwardly from position *b*, and finally to position *c*, the movable lever is drawn backwardly which draws the chain taut about the form, binding parts

of the same together, as will be understood from Fig. 1. If the lever be supported at the point 8 of the aperture 7 in the members 2 and 3 and movement of the lever to position *c* does not bind the chain with sufficient degree of strain about the form, the lever may be moved to position *b* and the bolts or studs 6 set to pivot in the point 9 of the aperture 7 to take up the slack in the chain. It is to be noted that when the lever is in the position indicated at *c* the strain on the lever at the point 12, which is the pivotal point of the hook member 11, is below the pivotal point of the lever. The strain imposed by the chain, therefore, tends to hold the lever in the position *c*, and the clamp is thus automatically locked in place as will be readily understood.

In placing the several clamps about the form, they should be spaced closely together near the bottom of the form and farther apart toward the top of the column, for the reason that the weight of the material causes greater bursting strain at the bottom, requiring a more secure fastening of the form at the lower end thereof than at the top.

The device is preferably made of malleable iron but may be made of any material suitable for the purpose, and from the foregoing description it may be understood that the device is comparatively inexpensive to manufacture, being simple in form and of but few parts and the labor involved in positioning the clamp about the form is reduced to a minimum.

Having thus briefly described my invention, its utility and mode of operation what I claim and desire to secure by Letters Patent of the United States is—

- 40 1. A clamp for concrete column forms comprising a base member adapted to engage against the form, a chain having one end secured to the base member, a pivotally mounted lever, and a hook member pivotally secured to the lever adapted to engage a link of the chain, the pivotal point of the lever being to one side of the line of strain thereon whereby said lever is held in locked position when under strain.
- 45 2. A clamp for forms for concrete columns comprising a base member adapted to engage the form, a chain having one

end secured to one end of the base member, upright members on each side of the base member, a bifurcated lever having an end 55 pivotally mounted on each side member respectively, a hook member pivotally secured to the lever adapted to engage a link of the chain, the pivotal point of the lever being above the pivotal point of the hook 60 member when the lever is turned to locked position.

3. A clamp for concrete column forms comprising a base member adapted to rest against the form, a chain having an end 65 secured to one end of the base member, said base member being recessed to receive a link of the chain and having an apertured block or reinforcement through which the link passes, upright members on each side of the 70 base member, each having an aperture notched on one side, a bifurcated lever the two ends each having a stud engaging in the aperture of the respective side member, the notches of the aperture providing a setting 75 for the studs and enabling the position of the lever to be altered relative to the base, and a hook member pivoted to the lever and lying in the furcation thereof, said member being adapted to engage a link of the chain, 80 the notches providing a pivotal support for the lever at a point outside the line of strain on the lever when in locked position.

4. A clamp for concrete column forms comprising a base member adapted to lie 85 against a side of the form and provided with parallel upright members on each side, a chain having an end secured to the base member, a bifurcated lever having the ends pivotally supported in the respective members of the base, the support of the lever and members being such as to allow an adjustment of the lever longitudinally of the base, and a hook member pivotally supported in the bifurcation of the lever above the 95 point of pivot of the lever with the said members, said hook member being adapted to engage a link of the chain and the pivot point thereof being below the pivot point of the lever when the lever is turned to 100 locking position.

In testimony whereof I sign this specification.

FRANK E. SHRINER.
